UNITED STATES PATENT OFFICE.

JOHN KELLING, OF MILWAUKEE, WISCONSIN.

FLESHING-MACHINE.

1,235,697.

Specification of Letters Patent. Patented Aug. 7, 1917.

Application filed March 12, 1917. Serial No. 154,216.

To all whom it may concern:

Be it known that I, JOHN KELLING, a citizen of the United States, and resident of Milwaukee, in the county of Milwaukee and State of Wisconsin, have invented certain new and useful Improvements in Fleshing-Machines; and I do hereby declare that the following is a full, clear, and exact description thereof.

10 My invention relates to new and useful improvements in fleshing machines together with an adjustable guard for such machines.

15 Machines of this character are adapted to remove surplus flesh from the under side of raw skins, and furs, or to reduce the thickness of dressed skins, the parings thereby removed falling between the cutter and guard. In devices of ordinary construction the cutter and guard are so shaped that these 20 parings soon accumulate between the same and cause friction, thereby retarding the operation of the cutter.

25 One of the objects of my invention is to provide an improved cutter and guard which will eliminate this disadvantage.

An additional object is to provide an improved guard which has an adjustable means so that its relation to the cutting blade of the machine may be varied.

30 With these and other objects and advantages in view, the invention resides in the novel features of construction, combination and arrangement of parts which will be hereinafter more particularly described and claimed.

35 In the drawings:

Figure 1 represents a front elevation of a fleshing machine having my improved adjustable guard secured thereto.

40 Fig. 2 is a horizontal section taken substantially on the line 2—2 of Fig. 1.

Fig. 3 is a detail transverse section showing more clearly the cross sectional shape and position of the cutter and its guard.

45 Referring more particularly to the figures of the drawing wherein similar reference characters designate like parts, the numeral 1 indicates a support of any ordinary or necessary size upon which the machine is 50 mounted, the annular rotary cutter 2 thereof being held in spaced relation thereabove on the upper end of a supporting standard 3. The standard 3 is of any convenient size and shape and has an attaching foot 4 on its 55 lower end by which it is secured to the sup-

port, and on its upper end is formed a head 5 having a transverse opening extending there-through to receive a shaft 6 upon which said cutter 2 is rotatably mounted.

This cutter is also of any convenient size 60 having an outer dished face 7, as shown in Fig. 3, the annular edge of which is sharpened to form a cutting blade. The other face of the cutter is inclined inwardly as shown at 8 toward its center and carries a drum 9, the 65 same surrounding the opening there-through which receives the shaft 6. The drum 9 is adapted to have a belt 10 trained there-around, whereby power may be transmitted from any suitable source to the cutter so as 70 to rotate the same. It will be noted from Fig. 1 that the belt preferably extends downwardly through spaced openings 11 in the support 1. A suitable sheet metal guard 12 is placed around the belt and the drum, the 75 same being attached by the foot 13 to the support 1.

In assembling these parts of the machine, the shaft 6 which is in the form of a rather long bolt is extended through the opening 80 in the cutter 2 and through that in the head 5, a bearing collar 14 having first been interposed between said head and the face 7 of the cutter. The fixed head 15 of the shaft and a washer 16 adjacent said head 85 and a nut 17 threaded on the opposite end of the shaft hold the same against shifting through the openings in the several parts and secure the latter to the standard 3.

In operating all the parts of the machine thus far described, the user, when he desires to remove the surplus flesh from the under side of raw furs or skins, or to reduce the thickness of dressed skins, draws said hides or skins diagonally across the 90 edge of the rapidly rotating cutter 2, the amount of material removed depending upon the angle at which the skins are held with respect to the face 7. Since it is very difficult to evenly remove the surplus material in this manner, especially by inexperienced workmen an adjustable guard 18 has been provided, the same being in the form of an arcuate segmental plate, the curvature of the outer edge being substantially the same as that of the cutting edge of the cutter. The inner edge is also preferably concentric to the outer, and one end edge 19 is in the plane of a radial line extending from the center of a circle concen- 100 105 110

tric to the inner and outer edges, while the other end edge 20 is cut at an acute angle thereto.

It will be noted most clearly in Fig. 3 that the face of the guard 18 is inclined inwardly from the outer toward the inner edge so as to form a surface against which the skin may rest while being drawn across the edge of the cutter, thus forming a guide to aid the operator in removing the desired amount of surplus material from the flesh side of the skins or furs. The parings thus removed fall between the dished face 7 of the cutter and the guard 18 and drop past the lower portion of the cutter onto the support 1 or in any suitable receptacle which may be placed thereon. It will be seen from the above mentioned figure that the adjacent faces of the cutter and guard are inclined away from each other so that there is no possibility of the surplus material removed from the skins accumulating therebetween as in the old style fleshing machine. In other words, the under side of the guard 18 is inclined in the same direction as its outer surface and the adjacent edges of the cutter and guard come together to effectively coöperate in removal of the material from the skins.

It is obvious that by moving the outer edge of the guard inwardly or outwardly with respect to the cutting edge of the cutter, a greater or lesser amount of materials may be removed, all of the parings, as above mentioned, passing between this edge of the guard and the adjacent face of the cutter. This guard is adjusted by an improved construction forming part of my invention. The same consists broadly of an arm carried by the guard and rotatably and slidably disposed in a socket formed in one arm of a substantially right angular bracket, the other arm of the latter being adjustably secured to the head 5 by means of the shaft 6 and its nut 17.

Specifically this part of the invention consists of a number of separable members all of which are adjustably connected together. The under surface of the guard 18 midway between its ends is provided with a boss 21 in which a socket is formed to receive a pin 22, the same being held therein by a set screw 23. The free end of this pin is slidably and rotatably disposed in a bearing sleeve 24, the same also having a set screw for securing the pin therein. From the bearing sleeve extends a pin 25 slidably and rotatably mounted in a bearing opening 26 formed in one end of a longitudinally slotted plate 27, the slot of which is adapted to receive the shaft 6. A set screw 28 retains the pin 25 in the opening 26, the bearing sleeve 24 with its pin 25 and the slotted plate 27 forming in effect the right angular bracket above mentioned. It is ob-

vious that inasmuch as all of these separate elements may be adjusted with respect to each other, the guard may be moved in any direction relative to the outer face 7 of the cutter. For instance, by adjusting either the pin 22 in its sleeve 24 or the plate 27 the edge of the guard may be moved toward or away from the center of the cutter. Also by moving the pin 25 in its bearing opening, the space between the face 7 of the cutter and the adjacent edge of the guard may be varied. Furthermore the guard and all of the parts which hold it to the machine may be rotated around the shaft 6. With this great range of adjustment any kind of skins or furs may be properly fleshed or pared on this machine.

Because of the fact that the cutter must have its annular edge very sharp in order to properly operate on the furs, provision is made for mounting a grinding mechanism upon the support, the same not being secured thereto during fleshing operations. This grinding machine may be of any preferred construction such as that shown in Fig. 1 where it will be noted that a sharpening stone 30 is disposed horizontally upon a vertical shaft operated by suitable gears driven by the crank 31. The support for these parts has an attaching foot 32 by which it may be quickly attached to the support 1 by the bolt and nut 33. Both faces of the cutter may be ground by the stone 30 by shifting the mechanism to either side of said cutter.

From the foregoing description taken in connection with the accompanying drawing, it is obvious that a very simply constructed fleshing machine has been provided with a universally adjustable guard, and that the same will be much more efficient than any similar device now in use. Furthermore with slight modifications the guard may be used on fleshing machines already in operation.

I claim—

1. The combination with a fleshing machine having a fleshing knife of a guard plate secured to said machine adjacent said knife, and means for adjusting said guard plate in any direction relative to the knife.

2. The combination with a fleshing machine having a fleshing knife of a guard plate disposed adjacent said knife, an arm extending from said plate and a bracket carried by the machine, said arm being slidably and rotatably supported in said bracket, whereby to hold said plate in adjusted positions with respect to the knife.

3. The combination with a fleshing machine having a fleshing knife of a guard plate disposed adjacent the said knife, a pin extending from said plate, and a bracket carried by the machine and including a right angular member having one arm secured to the machine, the other arm being provided

- with a bearing to slidably and rotatably receive said pin, whereby to hold said plate in adjusted positions with respect to the knife.
4. The combination with a fleshing machine having a fleshing knife of a guard plate disposed adjacent said knife, a pin extending from said plate, and a bracket carried by the machine and including a right angular member having one arm slotted and adjustably secured to the machine, the other arm being provided with a bearing to slidably and rotatably receive said pin whereby to hold said plate in adjusted position with respect to the knife.
5. The combination with a fleshing machine having a fleshing knife of a guard plate to be disposed adjacent said knife, a plate having a bearing opening formed therein, said plate being secured to the machine, and an arm carried by said guard plate and slidably disposed in said bearing opening whereby to move said guard plate toward or away from said knife.
6. The combination with a fleshing machine having a fleshing knife of a guard plate, an arm extending from said guard plate, and a bracket carried by the machine and including a slotted plate having a bearing opening formed in one end, a bearing sleeve receiving said arm, and a pin extending from said sleeve and disposed in said bearing opening.
7. The combination with a fleshing machine having a fleshing knife of a guard plate, means for securing said plate to the machine in adjusted positions with respect to the knife, said means including a socketed boss formed on the plate, a pin removably disposed in the socket in the boss, a slotted plate having a bearing opening formed in one end, a bearing sleeve receiving said pin, and a second pin extending from said sleeve and disposed in said bearing opening.
8. A guard for a fleshing machine comprising a plate, and means for adjustably mounting said plate adjacent the fleshing knife of said machine, said means including a pin extending from the plate, a plate secured to the machine and having a bearing opening in one end, a bearing sleeve receiving said pin and a second pin extended from said sleeve and disposed in said bearing opening.

In testimony that I claim the foregoing I have hereunto set my hand at Milwaukee, in the county of Milwaukee and State of Wisconsin.

JOHN KELLING.
